L. D. BARTLETT.
VALVE OF STEAM ENGINE.

No. 61,141.

Patented Jan. 15, 1867.

Inventor:

Louis D. Bartlett

United States Patent Office.

LOUIS D. BARTLETT, OF FITCHBURG, MASSACHUSETTS, ASSIGNOR TO THE
PUTNAM MACHINE COMPANY, OF SAME PLACE.

Letters Patent No. 61,141, dated January 15, 1867.

IMPROVEMENT IN VALVES OF STEAM ENGINES.

The Schedule referred to in these Letters Patent and making part of the same.

TO ALL WHOM IT MAY CONCERN:

Be it known that I, LOUIS D. BARTLETT, of Fitchburg, in the county of Worcester, and State of Massachusetts, have invented certain improvements in Valve-Chests for Steam Engines, of which the following is a full, clear, and exact description, reference being had to the accompanying drawings, making part of this specification, in which—

Figure 1 is a side elevation of a steam engine having my improved valve-chest applied thereto.

Figure 2 is a horizontal section through the cylinder and valve-chests.

Figure 3 is a vertical section through the centre of one of the valve-chests (enlarged.)

Figure 4 is a rear elevation of one of the valve-chests (enlarged.)

Figure 5 is a transverse vertical section on the line *y y* of fig. 4.

My invention consists in a simple and compact arrangement and construction of the valve-chests and steam passages of engines where poppet-valves are employed, whereby the dimensions of the chest can be reduced, and great facility afforded for removing the valves when cleaning or repairing is required.

To enable others skilled in the art to understand and use my invention, I will proceed to describe the manner in which I have carried it out.

In the said drawings, *A* is the cylinder, to each end of which is secured a valve-chest, *B*, within which are placed the steam-valves *C* and exhaust-valves *D*, the stems *a b* of which are operated by the levers *e*, which are raised by cams on the revolving shaft *E*, in a manner similar to that described in the Letters Patent of the United States granted to Charles H. Brown and Charles Burleigh on the fifteenth day of January, A. D. 1856, the steam-valves being so connected with the governor that the steam will be cut off at any point of the stroke, according to the amount of work upon the engine, in a well-known manner. *F* is the inlet steam pipe through which the steam passes into the passage *G*, whence it passes to the valve-chests *B*, and through the valves *C*, into the cylinder *A*. The construction of these chests and the arrangement of their steam passages being precisely alike, I will describe one only, referring particularly to figs. 2, 3, 4, and 5. The interior of the chest is cast with two boxes or casings, *H I*, upon which are the upper and lower seats of the steam and exhaust-valves *C D*, the stems *a b* of which pass through the bottom of the chest, while their upper ends are guided in circular blocks or disks, *d*, on the under side of the covering-plates *e*, which fit into openings, *f*, made through the top of the chest, to which the plates are bolted; and when these plates are removed the valves can be readily withdrawn for cleansing or repairs, the lower disks, *g h*, of the valves being of smaller diameter than the upper ones, *i k*, so as to allow of this being done. The interior of the chest is divided into two portions, 6 and 7, by a partition, *l*, so that the steam in passing from the passage *G*, enters the portion 6 of the chest, and surrounds the box *H*, but has no communication with the portion 7, except when the valve *C* is raised, when it passes into the portion 7, surrounding the box *I*, and thence by the passage *m* (fig. 2) to the cylinder *A*. When the steam-valve *C* is closed and the exhaust-valve *D* opened, the exhaust steam passes by the passage *m* to the portion 7 of the chest, and thence into the box *I*, the space within which is in constant communication with the exhaust passage *J*, and is entirely shut off from the portion 7, except through the opening commanded by the valve *D* when the latter is raised from its seat.

The above-described valve-chest is simple, compact, and economical in its construction, the parts being few and easily cast; while the arrangement of its steam passages is such that the disks of both its steam and exhaust-valves can be placed very near together on their stems, by which a great advantage is gained, as the shorter the stems between the valve-disks, the less the liability of their longitudinal expansion from the heat to which they are exposed, which often seriously affects the position and fit of the upper valve-disks on their seats; and this construction also allows of the lower disks being made of smaller diameter than the upper ones, so that the valves may be readily withdrawn for cleansing or repairs, by simply removing the covering plates from the top of the chest.

Claim.

What I claim as my invention, and desire to secure by Letters Patent, is—

The arrangement of the casings, steam passages, and valves, within the steam-chest, in relation to each other, and operating substantially as described.

LOUIS D. BARTLETT.
